SELF-EQUALIZING, SELF-ALIGNING BODY SUPPORT

Edward R. Dye, Orchard Park, and Murray Kamrass, Buffalo, N. Y., assignors to Cornell Aeronautical Laboratory, Inc., Buffalo, N. Y., a corporation of New York

Application December 30, 1953, Serial No. 401,148

2 Claims. (Cl. 5—191)

This invention relates to apparatus and method for supporting a human body when reclining.

When the human body is reclining, it should be supported so that the spinal column is in a straight line. Also, the body should be supported proportional to the distribution of weight. A further requirement for optimum support is to make the intensity of pressure as uniform as possible over the surface of the body. If these three requirements are met, a person should receive the most restful sleep.

These requirements are realized with the apparatus and method forming the subject of the present invention.

Secondary objects and advantages will be apparent from the following description and accompanying drawings in which:

Fig. 1 is a top plan view of a self-equalizing, self-aligning cot suspension embodying the present invention.

Fig. 2 is a side elevational view thereof and illustrating the displacement of the suspension when a human body reclines on the cot and also showing a chart representing numbered imaginary stations along the length of the body.

Fig. 3 is an end elevational view of the head end or right end of the cot shown in Fig. 2.

Fig. 4 is a diagram of elements and displacements of the cot suspension at a typical cross section.

Fig. 5 is a vector diagram of the forces involved in the right half of the diagrammatically represented suspension of Fig. 4.

Fig. 6 is an enlarged fragmentary cross sectional view through the end of one of the transverse support members and showing the manner in which this end is mounted on the cot frame.

While the invention may be embodied in different types of body supporting apparatus such as hospital equipment, stretchers and furniture, the invention is illustrated as being embodied in a cot.

The cot is shown as having a frame comprising a pair of spaced parallel horizontal side frame members 10, 10 supported adjacent each end by a U-shaped member 11 with a similar U-shaped member 12 arranged intermediate the end members 11. These members 10, 11 and 12 are preferably formed of round metal tubes. The end members 11 are preferably set in from the ends of the side frame members 10 so as to leave handles 13. The upper ends of the legs of the U-shaped members 11 and 12 are suitably rigidly connected to the side frame members 10 and these legs are of the same height so that the side frame members 10 will be horizontal when the cot is set on a flat horizontal surface such as a floor.

The suspension part of the cot comprises a multiplicity of transverse load carrying straps each represented by the numeral 14 and a series of longitudinal elastic strips 15.

Each of the transverse load carrying straps 14 includes a central non-elastic part 16 and an elastic part 17 at each end thereof. While the elastic part 17 as a single reach may be connected at one end to the adjacent end

2

of its companion nonelastic part 16 and the opposite end to the adjacent side frame member 10, it is preferred to form each elastic part 17 into a loop passing around the frame member and fastened at its opposite ends to the end portion of the non-elastic part as best shown in Fig. 6. The method of fastening may be by stitching as shown and represented at 18.

The length of each composite transverse strap 14 is the same when unloaded but it will be observed by referring to Fig. 1 that the proportionate lengths of elastic and non-elastic parts in each such strap varies from one to another. The purpose for this will be later explained herein.

The transverse composite straps 14 are composed of the same width material and are uniformly spaced along the side frame members 10 and deflect varying amounts under load as shown in Fig. 2. In order to maintain the spacing of such transverse straps 14, the spaced longitudinal elastic strips 15 are shown as being passed alternately over and under the transverse straps and are fastened at their places of overlapping in any suitable manner as by stitching 19. These longitudinal elastic strips 15 act as ties and do not have any load carrying function.

To attain maximum body comfort on the cot, the suspension of the cot should deform to accommodate the local weight and dimensions of the body. In accordance with the present invention this is accomplished by varying the elasticity of the cot suspension along its length. As an approximation to the actual system, reference is made to Fig. 4 wherein a weight W is applied to the transverse composite strap which has a non-elastic central portion 16a and an elastic portion 17a at each end connected to the side frame bars 10a, 10a. The horizontal spacing between the side frame bars 10a remains constant and one half such spacing is considered as x . Therefore the tension in the composite strap is a function of the weight W and the deflection y .

It will now be shown that by specifying the values of W and y the characteristics of the spring or elastic portions 40 at the ends of the straps can be determined. Fig. 5 is a vector diagram of the forces involved wherein F is the tension in the composite strap with

$$\frac{W}{2}$$

the vertical component and

$$\sqrt{F^2 - \left(\frac{W}{2}\right)^2}$$

the horizontal component. From relating the similar triangles shown in Figs. 4 and 5 and solving for F the following equation results:

$$(1) \quad F = \frac{W}{2} \frac{\sqrt{x^2 + y^2}}{y}$$

Since the elastic will stretch in proportion to the tension in the strap; another equation can be written as follows:

$$(2) \quad F = k\Delta$$

wherein k is the spring constant of the elastic or spring, and Δ is the elongation of the elastic. From the geometry of the system

$$(3) \quad \Delta = \sqrt{x^2 + y^2 - x}$$

Substituting (3) into (2) and equating (2) to (1)

$$(4) \quad k(\sqrt{x^2+y^2}-x) = \frac{W}{2} \frac{\sqrt{x^2+y^2}}{y}$$

Solving for k

$$(5) \quad k = \frac{W}{2y \left(1 - \frac{x}{\sqrt{x^2+y^2}} \right)}$$

The factors which determine the value of k are the length and modulus of the elastic material used. For a given elastic material, it is possible to vary k by varying the length in accordance with the equation

$$(6) \quad K = kL$$

wherein K is the modulus of the spring or elastic per unit length and L is the spring length.

Solving for L , there results

$$(7) \quad L = \frac{K}{k} = \frac{2yK}{W} \left(1 - \frac{x}{\sqrt{x^2+y^2}} \right)$$

In the case of a load which is more or less distributed such as would be applied by parts of the body, the above analysis is not exact. Nevertheless, the general principles of design are applicable with the exception that the expression for L becomes more complex although it need not contain new variables. For the practical case of designing a cot to support a human being, average dimensions and weights can be assumed so that the cot will be suitable for most persons of reasonable proportions. It is to be noted that modifications of the system can be devised for sitting and other positions of reclining.

For the case where there is a finite spacing between adjacent transverse straps 14 and where the elastic members 17 are wrapped around a tubular frame member 10, as shown, Equation 7 must be multiplied by the factor $2/S$, where S is the spacing between the centerlines of adjacent straps (see Fig. 2) and the factor of 2 is required to account for the looping or doubling of the elastic member 17 whose effective length is L (see Fig. 6). Thus the equation becomes

$$(8) \quad L = \frac{2yK}{WS} \left(1 - \frac{x}{\sqrt{x^2+y^2}} \right)$$

in which:

L =elastic length in inches

x =half the width of cot in inches

K =modulus of a one inch length of elastic

y =deformation of strap due to body contour (in inches)

W =local weight of body in pounds per inch of height

S =spacing between adjacent strap centerlines in inches

By way of example, assume a man of average height (69 inches) and average weight (153.4 pounds) lying on his side on the cot (whereas he is shown in Fig. 2 as lying on his back) but having the height or length of his body divided into imaginary two inch transverse elements beginning with station zero at the bottom of his feet. The deflection y or half the width of the body and the local weight W of the body is listed in the table herebelow. The following values, for example, can be used in Equation 8.

$x=15$ inches

$K=25$ pounds per inch

$S=2$ inches

$y=$ half width of body (see table)

$W=$ local weight of body (see table)

Then Equation 8 reduces to

$$(9) \quad L = \frac{50y}{W} \left(1 - \frac{15}{\sqrt{225+y^2}} \right)$$

The right hand column captioned L in the following table lists the calculated values of the effective length L in inches for each elastic loop 17 shown in Fig. 6.

	Station	Y, inches	W, lbs./in.	L, inches
10	0	3.95	2.00	3.25
	2	2.98	2.00	1.42
	4	2.81	.90	2.65
	6	3.04	.90	3.31
	8	3.38	.90	4.64

	52	7.31	4.40	8.42
	54	7.37	4.40	10.24
	56	7.31	3.00	8.42
	58	3.15	1.26	1.13
30	60	2.14	1.26	.84
	62	2.53	1.26	1.38
	64	2.92	1.26	2.12
	66	3.04	1.26	2.44
	68	2.48	1.26	1.30

From a practical point of view, a particular strap suspension designed as illustrated above is equally effective whether the human body is lying on the back or side inasmuch as the stretch of the spring or elastic portions at each station of the body will be approximately the same, considering the contour of the body.

From the foregoing it will be seen that the present invention provides an apparatus and method for human body suspension which simultaneously provides for the correct weight support and the proper deformation for each transverse element of the body so that no vertical

shear force is developed between the transverse elements and at the same time having the longitudinal axis of the body held in a straight line. The transverse strap support mechanism of the present invention has an elastic link which from strap to strap varies in length to adjust for

the sag and weight required of it. This is accomplished automatically by the apparatus requiring no external adjustment. It is pointed out further that in the apparatus of the invention the transverse straps when unoccupied are not prestressed or only negligibly as a result of the weight of the straps and this is uniform. By arranging the non-elastic part of the transverse strap in the center between the elastic ends, the body contacts the non-elastic part and does not interfere with the stretching of the elastic parts.

We claim:

1. A body support comprising a pair of spaced substantially parallel frame members maintained a substantially fixed distance apart, and a plurality of straps extending transversely of said members and connected at their ends to the same, each of said straps comprising a central non-elastic portion and end elastic portions, the elastic portions in all straps being substantially non-prestressed, and the ratio of the length of the non-elastic portion to the elastic portions in each strap being such that the strap stretches to the necessary length to provide the deformation corresponding to the ordinate of the section of the body engaged thereby and at the same time exerts a tension which produces a vertical resistance substantially equal to the weight of the section of the body supported, the length of each elastic portion in each trans-

70

verse strap being determined generally in accordance with the following equation

$$L = \frac{2yK}{W} \left(1 - \frac{x}{\sqrt{x^2 + y^2}} \right)$$

in which:

L is the length of the elastic portion, in inches

K is the modulus of a one inch length of the elastic portion

W is the weight of the section of the body, in pounds

x is half the spacing between the frame members, in inches

y is the ordinate of strap displacement to accommodate the section of the body, in inches.

2. A body support comprising a pair of spaced substantially parallel frame members maintained a substantially fixed distance apart, and a plurality of uniformly spaced transverse straps arranged between said frame members, each of said straps comprising a central non-elastic portion and an elastic loop portion secured to each end thereof and embracing the corresponding frame member, the elastic portions in all straps being substantially non-prestressed, and the ratio of the length of the non-elastic portions in each strap being such that the strap stretches to the necessary length to provide the deformation corresponding to the ordinate of the body engaged thereby and at the same time exerts tension which produces a vertical resistance substantially equal to the

weight of the section of the body supported, the length of each elastic portion in each transverse strap being determined generally in accordance with the following equation

$$L = \frac{2yK}{WS} \left(1 - \frac{x}{\sqrt{x^2 + y^2}} \right)$$

in which:

L is the length of the elastic portion, in inches

10 K is the modulus of a one inch length of the elastic portion

W is the weight of the section of the body, in pounds

S is the spacing between adjacent strap centerlines, in inches

15 x is half the spacing between the frame members, in inches

y is the ordinate of strap displacement to accommodate the section of the body, in inches.
